UNITED STATES PATENT OFFICE.

WILBER H. VAN SICKEL, OF PHILADELPHIA, PENNSYLVANIA, ASSIGNOR TO
THOS. H. DALLETT CO., A CORPORATION OF NEW JERSEY.

STONE-DRESSING MACHINE.

No. 857,692.

Specification of Letters Patent.

Patented June 25, 1907.

Application filed February 15, 1907. Serial No. 357,435.

To all whom it may concern:

Be it known that I, WILBER H. VAN SICKEL, a citizen of the United States, residing at Philadelphia, county of Philadelphia, 5 and State of Pennsylvania, have invented a new and useful Improvement in Stone-Dressing Machines, of which the following is a full, clear, and exact description, reference being had to the accompanying drawings, which 10 form a part of this specification.

My invention relates to that class of machines known as stone dressing machines in which the tool is supported so as to have a horizontal linear movement, a vertical movement and a rotary movement. In this class 15 of machines there is generally used a vertical standard or upright, with respect to which the tool carrying device has its movements. This standard is generally supported upon a 20 movable base.

The object of my invention is particularly the production of a novel arrangement of this upright and its support so that the standard may readily be connected to a 25 fixed support such, for instance, as a vertical beam and yet may readily be rotatable to enable the tool carrying device to move in the arc of a circle and also enable the tool carrying device to be guided in its vertical 30 movement, and raised or lowered at the will of the operator.

In the drawings: Figure 1 is a side view of my improved stone dressing machine. Fig. 2 is an end view from right end Fig. 1. Fig. 35 3 is a detail view of upper end of standard showing construction with modified form of support for sheaves. Fig. 4 is a view similar to Fig. 3 showing standard supported from upper end.

40 a is a beam or upright having the projecting brackets, one b near the lower end and the other c near the upper end. The bracket b carries the bearing d and the bracket c the bearing e.

45 f is a standard preferably bifurcated, as shown, having secured to its lower end the frame g carrying the bearing point h, which rests in the bearing d. The bearing e is orificed. A frame i is provided with a projection i which passes through and projects beyond the orifice in bearing e. The end of this projection i, beyond the bearing e is threaded. An orificed washer or plate j

surrounds this projection i. The under surface of this plate j and the upper face of bearing e are grooved for a ball race. A nut k on the threaded end of projection i forces the plate j against the upper surface of the bearing e. Between the plate and bearing e are the balls l. The lower face of frame h is 60 bored to form a bearing 4, and in which rests the bearing point m of a frame n secured to the upper end of standard f.

o is a yoke projecting downward from frame h, on opposite sides of standard f. 65 An orifice p is formed in the standard f and the yoke o in which rests the trunnion or shaft q of the sheaves r. The orifice through the standard is larger than the trunnion or shaft q so that the sheave is supported from 70 the bearing e, independent of the standard.

s is a horizontal frame, upon which is mounted the rollers t of the trolley or carriage u from which is supported the tool w. Thus the carriage u and tool w may move 75 along this frame s. At the inner end of this frame s is the plate x entering between the bifurcations of the standard f so as to be movable vertically, but be guided thereby. y is a projection from this plate carrying the 80 sheave z. Upon the frame is the drum 1 operated by the wheel 2. A cable or cord is secured, at one end, to the hook at the outer end of the horizontal frame s, passes up over one of the sheaves r, then around sheave z, 85 then back over the other of the sheaves r and is, at its other end, secured to drum 1. With this construction, as may be seen, the standard is guided at the top and bottom and may readily be rotated, carrying with it 90 the horizontal frame s and its carried tool. Moreover the weight of the frame s is supported independently of the standard, enabling the turning of the standard with ease. The frame s is moved vertically by turning 95 the wheel 2.

If desired, I can carry the frame s upon the standard f as shown in the construction illustrated, Fig. 3. In this case the trunnion or shaft q for the sheaves r is mounted 100 in an orifice in the standard. In this case the bearing point 5 from the frame 6 rests in a socket 7 formed in the bearing block 8, secured to the bracket c. In this case, as in the previously described construction, the 105 standard is supported at one end and

guided at both ends, but instead of supporting the arm independent of the standard, it is supported upon the standard.

Instead of supporting the standard at its lower end, I can support it at the upper end as illustrated in Fig. 4. In this case the upper bracket *c* carries a hollow bearing *9* through which projects the journal *10*, the frame *11* of which is secured to the standard. This journal *10* extends beyond the bearing *9* and is threaded at its upper end. An orificed plate *12* surrounds this extension of the journal *10*. The lower surface of this plate *12*, and the upper surface of bearing *9* is formed into a ball race *13* in which are the balls *14*. A nut *15* working on the end of the extension of the bearing point *10* forces the plate *12* toward the bearing *9*. In this construction the standard is guided at both ends, but is supported at the upper end, the horizontal frame being supported from the standard.

Having now fully described my invention, what I claim and desire to protect by Letters 25 Patent is:

1. In combination, a standard rotatably supported, a frame adapted to carry the tool, rotatable with said standard and movable vertically thereon, and means to support said frame independent of the standard.

2. In combination, a standard, a frame, adapted to carry the tool, rotatable and movable vertically and guided by said standard in its rotation and vertical movement, 35 and means to support said frame independent of said standard.

3. In combination, a standard rotatably supported, a frame, adapted to carry the tool, rotatable with said standard and movable vertically thereon, a sheave for supporting said frame, and a support independent of said standard, for said sheave.

4. In combination, a standard, a frame, adapted to carry the tool, rotatable and movable vertically and guided by said standard in its rotation and vertical movement, a sheave for supporting said frame, and a support, independent of said standard, for said sheave.

5. In combination, a vertical standard, adapted to rotate, means at both ends of standard to guide said standard, in its rotation, a horizontal frame, adapted to carry a tool, rotatable with said standard, and a sheave rotatable with said standard, and connection between said sheave and frame for elevating the frame.

6. In combination, a vertical standard adapted to rotate, means to support said standard at one end and guide said standard at both ends, a horizontal frame, adapted to carry a tool, rotatable with said standard, and a sheave rotatable with said standard, and connection between said sheave and frame for elevating the frame.

7. In combination, a vertical standard adapted to rotate, means to guide said standard at both ends, in its rotation, and to support said standard at its lower end, a horizontal frame, adapted to carry a tool, adapted to rotate with said standard, and a sheave rotatable with said standard, and connection between said sheave and frame for elevating the frame.

8. In combination, a vertical standard, a projecting bracket near the upper end of said standard, a guiding bearing carried by said bracket in which the upper end of the standard is guided, a bracket near the lower end, a bearing carried by said bracket, the standard being seated in said last mentioned bearing, and the lower end guided thereby, a horizontal frame, adapted to carry a tool, adapted to rotate with said standard, and a sheave rotatable with said standard, and connection between said sheave and frame for elevating the frame.

9. In combination, a vertical standard, adapted to rotate, a bearing at the upper end of said standard in which the upper end of said standard is guided in its rotation, a bearing at the lower end of said standard in which the standard is supported, and the lower end guided in its rotation, a horizontal frame, adapted to carry a tool, adapted to rotate with said standard, and a sheave rotatable with said standard, and connection between said sheave and frame for elevating the frame.

10. In combination, a vertical standard, adapted to rotate, a bearing at the upper end of said standard in which the upper end of said standard is guided in its rotation, a bearing at the lower end of said standard in which the standard is supported, and the lower end guided in its rotation, a horizontal frame, adapted to carry a tool, adapted to rotate with said standard, a sheave near the upper end of said standard for supporting said horizontal frame, and means, independent of said standard, to support said sheave.

11. In combination, a vertical standard, adapted to rotate, a bearing at the lower end of said standard in which said standard is supported and guided, a horizontal frame, adapted to carry a tool, a sheave for supporting said horizontal frame, a bearing near the upper end of said standard, a frame, carrying the sheave, and connection between said standard and sheave frame whereby the sheave rotates with the standard.

12. In combination, a bifurcated vertical standard, adapted to rotate, a bearing at the lower end of said standard in which said standard is supported and guided, a horizontal frame, adapted to carry a tool, a bearing near the upper end of said standard, a frame carried by said last mentioned bearing, a yoke projecting from said frame, a sheave for supporting the horizontal frame located

between bifurcations of standard, there being orifices in the standard and yoke, a shaft for said sheave passing through said orifices, the orifice through the standard being larger than the orifice through the yoke.

13. In combination, a bifurcated vertical standard, adapted to rotate, a bearing at the lower end of said standard in which said standard is supported and guided, a horizontal frame, adapted to carry a tool, a bearing near the upper end of said standard, a frame carried by said last mentioned bearing, a yoke projecting from said frame, a sheave for supporting the horizontal frame located between bifurcations of standard, there being orifices in the standard and yoke, a shaft for said sheave passing through said orifices, the orifice through the standard being larger than the orifice through the yoke, and a bearing in the sheave supporting frame forming a guide for the upper end of the standard.

14. In combination, a bifurcated vertical standard, adapted to rotate, a bearing at the lower end of said standard in which said standard is supported and guided, a horizontal frame, adapted to carry a tool, a bearing, a frame carried by said last mentioned bearing, a yoke projecting from said frame, a sheave for supporting the horizontal frame located between bifurcations of standard, there being orifices in the standard and yoke, a shaft for said sheave passing through said orifices, the orifice through the standard being larger than the orifice through the yoke.

In testimony of which invention, I have hereunto set my hand, at Philadelphia, on this 8th day of February, 1907.

WILBER H. VAN SICKEL.
